UNITED STATES PATENT OFFICE

ROBERT STRIGEL, OF BERLIN-CHARLOTTENBURG, GERMANY, ASSIGNOR TO SIEMENS-SCHUCKERTWERKE AKTIENGESELLSCHAFT, OF BERLIN-SIEMENSSTADT, GERMANY, A CORPORATION OF GERMANY

ELECTRON TUBE

Application filed January 7, 1930, Serial No. 419,034, and in Germany January 10, 1929.

My invention relates to electron tubes, and more particularly to improvements in the arrangement of electron tubes for extra high voltages.

5 In electron tubes (cathode-ray tubes) the formation of positive ions can never be entirely avoided even by the most careful evacuation of the tube. If a pressure of several 100 kv. is applied to the electrodes 10 of the tube, this causes a considerable increase of the emission of electrons in consequence of the correspondingly increased bombardment of the cathode by ions. This 15 increase of the electron emission may attain such a degree that labile conditions develop due to the self-heating of the tube.

Electron or cathode-ray tubes for very high voltages in which the stream of ions becomes particularly noticeable are generally 20 designed in such a way that the voltage is subdivided over a plurality of steps in the manner of a cascade, and the accelerations are imparted to the electrons in successive steps under the action of the voltage.

25 In such electron tubes for extra high voltages with subdivided voltages it has been attempted to eliminate the adverse effects of the positive ions by interposing between the individual tubes of the cascade a metal 30 foil and thus to prevent the passage of the positive ions from the end electrode of one tube to the inlet electrode of the next tube. This metal foil is then permeable for the electrons to be further accelerated but impermeable for the positive ions.

The method described has, however, considerable defects. The metal foil impermeable for the ions although permitting the electrons to pass also causes a loss of velocity 40 of the electrons. This loss of velocity causes a considerable temperature rise of the metal foils, particularly in the higher steps of the voltage cascade which is liable to exceed the permissible value. To this must 45 be added the fact that undesirable X-rays develop at the metal foil.

According to my invention the adverse effect of the stream of ions is eliminated without the described disadvantages being 50 present. According to my invention the

ions are deflected into different paths from those of the electrons by means of a magnetic field.

My invention is based upon the physical conditions described in the following lines. 55 In a homogeneous magnetic field of the strength H a mass particle of the mass m and having a definite velocity describes a track the curvature radius r of which is determined by the formula

60

$$r = \frac{m}{e} \cdot \frac{2V}{H}$$

wherein e is the charge of the particle and 65 V the applied voltage between the electrodes. In a magnetic field of 280 gauss and a voltage of 100 kv. between the electrodes of one cascade step a curvature radius $r=5$ cm. for instance is obtained by inserting the values 70 for the electron.

My invention is based upon the fact that the positive ions possess a mass which is by several orders larger than the mass of the electrons. The mass of the hydrogen ion, 75 for instance, is 2000 times as large as the mass of an electron. At equal potential between the two electrodes the hydrogen ion suffers a deflection, the radius of which is forty-seven times greater than that of the 80 electron. This means that all the hydrogen ions, the velocity of which is not in the neighborhood of $1/47=2.1$ per cent of the velocity of the electrons, can be deflected into another direction than the electrons.

According to my invention I provide metal screens or baffles toward which the ions are deflected by the magnetic field while the electrons continue their travel in another direction. The width of the velocity spectrum 85 which is given free for the electrons by the deflection of the major portion of the ions is determined by the construction of the tube. For ions of other gases than hydrogen this spectrum is located at still lower 95 velocities.

Since the positive ions are accelerated in the direction of the cathode and thus run counter to the velocity of the electrons, the ions not screened out in the preceding cas- 100

cade are screened out in the next step. In order to obtain a sharp screening it is necessary that the electrons are as strongly as possible concentrated prior to their entry into the magnetic field. This may easily be attained by means of a suitably located solenoid or a combination of a plurality of solenoids.

The drawings affixed to my specification 10 illustrate a number of embodiments of my invention, of which

Fig. 1 shows, partly diagrammatically and in longitudinal section, a cascade arrangement of two electron tubes;

15 Fig. 2 shows in larger scale and in longitudinal section the detail construction of the heated cathode of tube 1 in Fig. 1;

Fig. 3^a shows in larger scale and in longitudinal section the separating device for 20 the electrons and ions;

Fig. 3^b shows a side elevation of the device in Fig. 3^a partly in section;

Fig. 4 shows a plurality of cascaded sections composing the tube;

25 Fig. 5 shows a preferred manner of connecting the individual sections, and

Fig. 6 shows a modification of Fig. 4.

Referring to Fig. 1 of the drawings it will be observed that the discharge vessel 30 consists of two glass bulbs 1 and 2 which are connected with one another by means of necks 3 and 4. The bulbs are preferably placed under an angle of 120° to each other since it is then possible to separate sufficiently the tracks of the ions and electrons and since, on the other hand, the ends of the individual tubes arranged in cascade do not come into an impermissibly close vicinity to each other so that an external arc 40 over is liable to occur.

The necks contain at the points 5 and 6 an electrode each, the potential of which lies between that of the cathode 7 and the anode 8. The electrodes 5 and 6 are formed by a 45 small metal cylinder. The hot cathode 7, which in Fig. 2 of the drawings is shown on a larger scale, consists of an incandescent wire loop 9, and a screen 12 the object of which is to concentrate the stream or beam 50 of electrons. The terminals of the high voltage source 13 and 14 are connected with the hot cathode 7 and the anode 8. The source of high voltage is in the middle provided with a tap which is connected to the 55 electrodes 5 and 6 and which carries a potential which is equal to half the value of the potential difference between the cathode 7 and the anode 8. Between the two electrodes 5 and 6 is located the device illustrated on a larger scale in Figs. 3^a and 3^b of the drawings and which according to my invention brings about a separation of the tracks or paths of the electrons and ions.

15 is a glass tube, which connects the 60 necks 3 and 4 of tubes 1 and 2, 16 are the

pole shoes disposed on each side of tube 15, and between which develops the homogeneous magnetic field, 19 is the iron yoke which carries the pole shoes, and 17 is the exciter winding for the magnetic field. The winding may be energized in various ways, preferably from an insulated battery (not shown). 20 are screens which are brought to the potential of the electrodes 5 and 6, for instance by a conducting coating 20^a inside of tube 15, shown in Figs. 3^a and 3^b. The screens serve to catch the positive ions. While the electrons flow deflected on the path indicated in broken lines, the (hydrogen) ions the velocity of which does not lie around 2.2 per cent of the electron velocity are arrested by the screens or baffle plates 20, those of higher velocity by the screen at the outside, those of lower velocity by the screen at the inside of the bend. 21, 22, 23 are solenoids surrounding the pertaining tube necks and serving for the concentration of the electron beams.

Preferably a deflecting device should be provided just behind the cathode, as shown in Figs. 4 and 6, since in this way the cathode can be protected most effectively. In Fig. 4 an electron tube with cascaded sections is shown which, besides the deflecting device for the protection of the cathode, is equipped with three further deflectors the direction of the bend of which changes. In this way it is possible to construct the tube in a main direction. According to the requirements of the application of the tube, the cathode, the intermediate electrode and the anode may be brought to the potential zero.

In Fig. 5 of the drawings is illustrated the design of an electron (cathode-ray) tube composed of cascaded sections and according to my invention, which results in a particularly satisfactory arrangement composed of the individual tubes. In such an arrangement the individual sections of the cascade may be separately evacuated and transported, and thus at site only assembly is necessary.

As will be seen from this figure, 3 and 4 are again the ends of the glass bulb necks of the usual evacuated tubes already adjusted at site. They are separated by the glass partitions 24 and 25 and possess tubular extensions 26 and which are now fused together and provided with a lateral connection 27 by blowing. The T stud 27 is connected to a high-vacuum pump by the pump branch 29 through the trap 28 for liquid air. During the pumping process the piece of tube 27 is heated to a temperature of about 500° C. The tube is then sealed at the capillary contraction 30. Now the glass walls 24 and 25 are destroyed. This may be effected by means of a piece of iron 31 which after the smashing of the glass is passed into the

carbon bag 32 and then no longer obstructs the discharge path.

I claim as my invention:

An electron discharge device for high voltages wherein electrons and undesired positive ions are generated, comprising a plurality of individual tubes mechanically and electrically connected in series for dividing the total voltage into a number of cascaded steps, and means for deflecting the positive ions and the electrons along different paths, comprising the arrangement of the axes of adjacent tubes at an angle less than 180° to one another, and means for producing in the apex of the angle a magnetic field in a direction parallel to a line bisecting said angle, for deflecting the ions and electrons into different paths.

In testimony whereof I affix my signature.

ROBERT STRIGEL.
